[57] CLAIM

The ornamental design for a cord clenching device, as shown and described.

DESCRIPTION

FIG. 1 is a front, right side perspective view of a cord clenching device showing my new design;

FIG. 2 is a right side elevational view thereof, the side opposite being a mirror image;

FIG. 3 is a top plan view thereof;

FIGS. 4 and 5 are respectively front and rear elevational views thereof;

FIG. 6 is a bottom plan view thereof;

FIG. 7 is a front, right side perspective view of a second embodiment thereof;

FIG. 8 is a right side elevational view thereof, the side opposite being a mirror image;

FIG. 9 is a top plan view thereof;

FIG. 10 and 11 are respectively front and rear elevational views thereof; and,

FIG. 12 is a bottom plan view thereof.
